UNITED STATES PATENT OFFICE.

ORANGE O. OZIAS, OF DAYTON, OHIO.

DESIGN FOR AN INDICATOR FACE-PLATE.

SPECIFICATION forming part of Design No. 28,933, dated June 28, 1898.

Application filed September 13, 1897. Serial No. 651,549. Term of patent 14 years.

To all whom it may concern:

Be it known that I, ORANGE O. OZIAS, of Dayton, county of Montgomery, and State of Ohio, have invented and produced a new and original Design for Indicator Face-Plates, of which the following is a specification, reference being had to the accompanying drawings, forming a part thereof.

This new and original design for the face-
10 plates of indicators consists in a new and original shape of exposing-opening through which an indicator is adapted to be shown, as illustrated in the accompanying drawings, in which—

15 Figure 1 is a front elevation of a face-plate embodying my new and original design, and Fig. 2 is a sectional plan view of a portion thereof on line $x-x$ of Fig. 1.

The material feature of my design consists
20 of a circular indicator face-plate having a radial opening extending from near the center of said plate to near its outer edge, where said radial opening is connected with an arc-shaped opening, and a pointed lip extending
25 from one edge of and partly across said arc-shaped opening.

A indicates the radial opening. B B' indi-

cates said arc-shaped opening, and I indicates said pointed lip. The edge C of said opening A extends in a radial line from the center D 30 of said face-plate, and at the top of said opening A is an ogee-curved edge E, joining said edge C with the edge F, which is slightly inclined, as shown, and connects with the edge G substantially parallel with the edge C. The 35 lower or outer end of said edge C terminates in a beveled edge H, which tapers into the upper edge of an annular opening B', which is opposite to and is a continuation of said arc-shaped opening B. Projecting upwardly and 40 inwardly from the outer edge of said opening B B' is a pointed lip or indicating projection I, whose point is in line with the edge C. Said opening B B' is in the arc of a circle concentric with the center of said face-plate. 45

Having now described my invention, what I claim as new, and desire to secure by Letters Patent, is—

The design for an indicator face-plate, substantially as herein shown and described.

ORANGE O. OZIAS.
